UNITED STATES PATENT OFFICE

114,751

DESIGN FOR A SWEATER

Henry Cohen, New York, N. Y.

Application September 19, 1938, Serial No. 79,986

Term of patent 3½ years

To all whom it may concern:

Be it known that I, Henry Cohen, a citizen of the United States and resident of New York city, (Borough of Manhattan), in the county and State of New York, have invented a new, original, and ornamental Design for a Sweater, of which the following is a specification, reference being had to the accompanying drawing, forming a part thereof, and of which Figure 1 is a view in front elevation of a sweater showing my new design, and Fig. 2 is a view in rear elevation thereof.

I claim:

The ornamental design for a sweater, substantially as shown.

HENRY COHEN.
